UNITED STATES PATENT OFFICE.

FREDERICK LAMPLough, OF FELTHAM, ENGLAND, ASSIGNOR TO HYDRO-DYNAMICS LIMITED, OF LONDON, ENGLAND.

HYDRAULIC PUMP.

1,346,548.

Specification of Letters Patent. Patented July 13, 1920.

Application filed April 28, 1919. Serial No. 293,371.

To all whom it may concern:

Be it known that I, FREDERICK LAMPLough, a subject of the King of England, residing in Feltham, Middlesex, England, have invented certain new and useful Improvements in Hydraulic Pumps, of which the following is a specification.

This invention is for improvements in or relating to hydraulic pumps of the rotary type and has for its object to provide a prime mover or pump of this type which shall be more compact than has hitherto been possible and wherein the operating parts shall be so disposed and balanced that the central shaft is relieved of side thrust. In these prime movers or pumps the driving shaft, as is known, is rotated by external power, such for example as an electric motor, and the fluid, conveniently oil, is circulated by the pump through a secondary hydraulic engine or motor which it is desired to drive.

A rotary hydraulic pump according to this invention comprises the combination of a driving shaft, a plurality of pump-cylinders mounted at different angular positions thereon with their longitudinal axes in a plane transverse to the axis of the shaft, a pair of opposed pistons in each cylinder, two circular guides surrounding the shaft and adapted to be moved into oppositely eccentric positions relatively thereto and means operatively connecting one piston in each cylinder to one guide and the other piston in each cylinder to the other guide, so that the pistons are reciprocated in opposite phase by the eccentric guides.

Preferably each cylinder is disposed symmetrically as to its length about a line radial to the driving shaft and with its longitudinal axis at right angles to that line, and its two pistons are coupled respectively by means of connecting rods and swinging levers to two slide blocks mounted one in each circular guide, said slide blocks being situated on diametrically opposite sides of the driving shaft.

Other features of the invention are hereinafter described and the novel details pointed out in the claims appended to this specification.

In the accompanying drawings which illustrate one embodiment of this invention:

Figure 1 is a longitudinal view partly in

section and partly broken away for clearness,

Fig. 2 is a transverse section on the line 2, 2 of Fig. 1, and

Fig. 3 is a transverse section on the line 60 3, 3 of Fig. 1.

Like reference characters indicate like parts throughout the drawings.

The hydraulic pump is mounted within a closed casing A from which a central driving shaft A¹ projects for connection to the electric motor or other driving means. This shaft has an enlarged hollow extension A² secured on it within the casing, and this enlargement constitutes a central valve 70 chamber divided into inlet and outlet passages A³ A⁴ by a fixed shaft or partition A⁵ which enters it at the end remote from the shaft A¹. These two passages terminate in ports, as shown at A⁶, to which suitable pipe 75 connections can be made.

A framework A⁷ secured or formed integral with the hollow shaft A² carries three pump-cylinders A⁸ spaced 120° apart around the shaft with the longitudinal axes lying 80 in a plane transverse to the axis of the shaft and interspaced with the cylinders are bosses in which are secured fulcrum pins A⁹.

Radial passages or ports B are formed in the wall of the shaft A² to communicate 85 with ports B¹ provided in each cylinder at the middle of its length, and the partition A⁵ is so dimensioned and shaped that it prevents the establishment of communication between the passages A³ A⁴ by the 90 ports B.

The cylinders A⁸ are open at both ends and have two pistons B² B³ one at each end reciprocating in opposite phase. The mechanism for operating each piston consists of 95 swinging levers B⁴, B⁵, pivoted on the above-mentioned fulcrum pins A⁹ (as shown on Figs. 1 and 3). The levers B⁵ are omitted in Fig. 2 for the sake of clearness, but their center lines are indicated at B⁶. The 100 levers are mounted in pairs on each pivot pin (Fig. 1) and each lever is coupled by a short connecting rod at one end to its corresponding piston. The similarly situated pistons in each of the cylinders, i. e. those at 105 say the forward end in the direction of rotation, are all coupled to levers on the same ends of the fulcrum pins A⁹ so that the pistons are divided into two groups actuated by levers on one side or other of the plane of 110

the cylinders, and there is a piston of each group in each cylinder.

The free ends of the levers B^4 , B^5 engage segmental slide-blocks B^6 , B^7 respectively which are mounted in annular channels B^8 , B^9 on cylindrical members C , C^1 . These members are preferably free to rotate on ball-bearings C^2 in swinging frames C^3 , C^4 . These frames are pivoted at C^5 near the bottom of the casing A and are located as to their upper ends C^6 by links C^7 connected to cranks C^8 . Hand-turning gear C^9 is provided for adjusting simultaneously both the cranks so that the frames C^3 , C^4 can be swung about their pivots, and the mechanism is such that they are swung in opposite directions away from the central position in which the channels B^8 , B^9 are concentric with the shaft A^2 .

20 The operation of the apparatus is as follows:

So long as the frames C^3 , C^4 are in their central position so that the channels B^8 , B^9 are concentric with the shaft A^1 , A^2 there will be no relative movement between the slide-blocks B^6 , B^7 and the fulcrum pins of the levers B^4 , B^5 and all the parts will run idly without any reciprocating movement being imparted to the pistons. If now the frames be swung (in opposite directions) about the pivot pins C^5 by means of the hand-turning gear C^9 the eccentricity of the channels B^8 , B^9 will cause the levers B^4 , B^5 (by their engagement with the slide-blocks B^6 , B^7) to swing on their fulcrum pins and impart a reciprocatory movement to the pistons. The partition A^5 is so disposed that it acts as a valve, opening the cylinder ports B , B^1 to the inlet passage when the pistons are moving apart, and to the outlet passage when they are approaching one another, so that the fluid is drawn in and discharged with an ordinary pumping action.

45 It will be appreciated that the throw of the pistons, and the capacity of the generator is determined (apart from the speed of the driving shaft) by the amount of eccentricity of the channels or guides B^8 , B^9 and that this capacity is variable at will from zero up to a maximum. Further, if the eccentricity be reversed, *i. e.* if the frames are swung each in the opposite direction from its initial swing, the reciprocation of the pistons will be reversed or in opposite phase with respect to their angular position about the partition A^5 and the pumping action on the fluid will take place in the opposite direction.

60 It is an important feature of the invention that the two pistons in each cylinder are operated through separate rocking levers which are of such length and so disposed that the corresponding slide-blocks are situated on diametrically opposite sides of the

driving shaft. The operative thrusts for the two pistons in any cylinder are therefore always opposed to one another and excessive side thrust or other unbalanced forces are not received by the driving shaft.

70 A pair of non-return valves D may be provided to give communication between the passages A^3 , A^4 and the interior of the casing A , in order that oil may be drawn in from the sump to make good the leakage which takes place in the cylinders and other parts.

Various secondary engines or motors may be used with this primary pump or generator but the preferred one is described in a concurrent patent application Serial No. 293,370, filed April 28, 1919.

When the pump above described is running idle, the cylindrical members C , C^1 , may rotate in their bearings C^2 , or the slide-blocks B^6 , B^7 may slide in the channels B^8 , B^9 according to which has the less friction, but when the pump is working the friction of the blocks in the channels insures that the members C , C^1 rotate in their bearings C^2 . The object of the sliding-blocks is to allow for the slight angular movement and consequent obliquity of the levers B^4 , B^5 at some parts of the working stroke.

What I claim as my invention and desire to secure by Letters Patent is:—

1. In a rotary hydraulic pump the combination of a driving shaft, a plurality of engine-cylinders mounted at different angular positions thereon with their longitudinal axes in a plane transverse to the axis of the shaft, a pair of opposed pistons in each cylinder, two circular guides surrounding the shaft and adapted to be moved into oppositely eccentric positions relatively thereto and means operatively connecting one piston in each cylinder to one guide and the other piston in each cylinder to the other guide, so that the pistons are reciprocated in opposite phase by the eccentric guides.

2. A hydraulic pump according to claiming-clause No. 1 wherein each pump cylinder is disposed symmetrically as to its length about a line radial to the driving shaft and with its longitudinal axis at right angles to that line, and its two pistons are coupled respectively by means of connecting rods and swinging levers to two slide-blocks mounted one in each circular guide said slide-blocks being situated on diametrically opposite sides of the driving shaft.

3. In a rotary hydraulic pump, the combination of a driving shaft, a plurality of pump cylinders mounted at different angular positions thereon with their longitudinal axes in a plane transverse to the axis of the shaft, a pair of opposed pistons, in each cylinder, circular guides surrounding the shaft and adapted to be moved into an eccentric position relatively thereto, and means op-

- eratively connecting one piston in each cylinder to one of said guides and the other piston in each cylinder to another of said guides, so that the pistons are reciprocated 5 in opposing phase by said guides.
4. In a rotary pump, the combination of a driving shaft, a circular guide surrounding the axis of said shaft, a pump cylinder mounted on said shaft with its longitudinal 10 axis disposed non-radially in a plane transverse to the axis of the shaft, a piston in said cylinder, means connecting said piston to said guide, and means for changing the eccentricity of said guide relative to the shaft 15 for varying the stroke of said piston.
5. In a rotary pump, the combination of a driving shaft, a circular guide surrounding said shaft, a pump cylinder mounted on said shaft with its longitudinal axis disposed tangentially to the circumference of a 20 circle in a plane transverse to the axis of the shaft, a piston in said cylinder, means connecting said piston to said guide, and means for changing the eccentricity of said guide 25 in opposite directions relative to the shaft for varying the stroke of said piston.
6. In a rotary pump, the combination of a driving shaft, housings surrounding said shaft, circular guides rotatably mounted one 30 in each of said housings, a pump cylinder carried by said shaft, opposed pistons in said cylinder, means connecting one piston in the cylinder to one of said guides and the other piston to another of said guides, so 35 that the pistons are reciprocated in opposite phase by said guides, and means for changing the eccentricity of said housings relative to the shaft in opposite directions for varying the stroke of the pistons.
- 40 7. In a rotary pump, the combination of a driving shaft, a guide having a groove surrounding said shaft, a pump cylinder carried by said shaft, a piston in said cylinder, a block slideable in said groove, and a rocking lever which is fulcrumed on the shaft 45 and which is pivotally connected at one end to said block, and at its other end to said piston.
8. In a rotary pump, the combination of 50 a driving shaft, a cylinder carried thereby, two opposed pistons in said cylinder, two guides each having a groove surrounding said shaft, two blocks slideable one in each of said grooves and located diagrammatically opposite one another, and two rocking 55 levers fulcrumed in said shaft, which levers are pivotally connected at one end each to one of said blocks and at their other ends each to one of said pistons.
9. In a rotary pump, the combination of 60 a driving shaft, a cylinder carried thereby, two opposed pistons in said cylinder, two annular guides each having a groove surrounding the said shaft, two blocks slideable one in each of said grooves and located diagrammatically opposite one another, and two rocking levers fulcrumed in said shaft, which levers are pivotally connected at one end, each to one of said blocks and at their other ends, each to one of said pistons, and 65 means for changing the eccentricity of said guide relatively to said shaft in opposite directions. 70
10. In a rotary pump, the combination of 75 a casing, a driving shaft journaled therein, a pivot fixed to the casing, a circular guide mounted to rock about said pivot in said casing and surrounding the axis of said shaft, a pump cylinder carried by said shaft, a piston in said cylinder, means connecting 80 said piston to said guide, and means for rocking said guide about said pivot.
11. In a rotary pump, the combination of 85 a casing, a driving shaft journaled therein, and having a hollow portion constituting a valve chamber provided with a port, a pump cylinder carried by said shaft and having a port which communicates with said valve-chamber port, a piston in said cylinder, a guide surrounding the axis of said shaft, means connecting said piston to said guide, and a valve which is carried by said casing which divides the valve-chamber into 90 inlet and outlet passages and controls the valve-chamber port. 95
12. In a rotary pump, the combination of 100 a casing, a driving shaft journaled therein and having a hollow portion constituting a valve-chamber provided with a port, guides movably mounted in said casing and surrounding the axis of said shaft, a pump cylinder carried by said shaft, and having a port which communicates with said former port, opposed pistons in said cylinder, means connecting one piston in the cylinder to one of said guides and the other piston to another of said guides so that the pistons are reciprocated in opposite phase by 105 said guides, means for changing the eccentricity of said guides relatively to the shaft in opposite directions for varying the stroke of the pistons, and a valve which is carried by said casing which divides the valve-chamber into inlet and outlet passages and controls the valve-chamber port. 110
- 115 In testimony whereof I affix my signature.

FREDERICK LAMPLough.
